(57) **CLAIM**

The ornamental design for a hanger, as shown and described.

DESCRIPTION

FIG. 1 is a front, top perspective view of a hanger showing an embodiment of our new design;

FIG. 2 is a rear, top perspective view thereof;

FIG. 3 is a front view thereof;

FIG. 4 is a rear view thereof;

FIG. 5 is a right side view thereof;

FIG. 6 is a right side view thereof with unclaimed portions removed for clarity;

FIG. 7 is a left side view thereof;

FIG. 8 is a left side view thereof with unclaimed portions removed for clarity;

FIG. 9 is a top view thereof; and

FIG. 10 is a bottom view thereof.

FIG. 11 is a front, top perspective view of a hanger showing a second embodiment of our new design;

FIG. 12 is a rear, top perspective view thereof;

FIG. 13 is a front view thereof;

FIG. 14 is a rear view thereof;

FIG. 15 is a right side view thereof;

FIG. 16 is a right side view thereof with unclaimed portions removed for clarity;

FIG. 17 is a left side view thereof;

FIG. 18 is a left side view thereof with unclaimed portions removed for clarity;

FIG. 19 is a top view thereof; and

FIG. 20 is a bottom view thereof.

FIG. 21 is a front, top perspective view of a hanger showing a third embodiment of our new design;

FIG. 22 is a rear, top perspective view thereof;

FIG. 23 is a front view thereof;

FIG. 24 is a rear view thereof;

FIG. 25 is a right side view thereof;

FIG. 26 is a right side view thereof with unclaimed portions removed for clarity;

FIG. 27 is a left side view thereof;

FIG. 28 is a left side view thereof with unclaimed portions removed for clarity;

FIG. 29 is a top view thereof; and,

FIG. 30 is a bottom view thereof.

The features shown in broken lines are portions of the hanger forming no part of the claimed design. The features

(Continued)

shown in long dash-short dash bolded broken lines indicate the bounds of the claimed design and otherwise form no part of the claimed design.

1 Claim, 15 Drawing Sheets
